United States Patent Office

Des. 186,342
Patented Oct. 13, 1959

186,342

STAPLING MACHINE OR SIMILAR ARTICLE

Herbert W. Marano, Summit, N.J., assignor to Wilson Jones Company, Elizabeth, N.J., a corporation of Massachusetts

Application December 19, 1957, Serial No. 48,957

Term of patent 14 years

(Cl. D74—1)

Figure 1 is a side elevational view of a stapling machine showing my new design, the side opposite thereto being substantially identical in appearance;

Figure 2 is a top plan view thereof;

Figure 3 is a front elevational view thereof; and

Figure 4 is a rear elevational view thereof.

I claim:

The ornamental design for a stapling machine or similar article, as shown and described.
